11 Claims. (Cl. 292—169)

This invention relates to door latches of the type having an operating shaft which is turned by the door handles to release the latch for door opening.

Door latches of this type normally have a squared shaft which engages both door handles, and the arrangement is commonly such that the door can be locked from one side so that it cannot be released by the handle on the opposite side which is thereby rendered ineffective. Locking means for this purpose commonly act to lock the door handles against rotation, and the object of the invention is to provide an improved form of door latch which can be locked from one side of the door in a particularly simple and efficient manner.

According to the invention a door latch has an operating shaft which is adapted to be rotationally coupled to door handles respectively mounted on opposite sides of the door, the arrangement being such that the shaft in use can be axially displaced from one side of the door to a locking position in which rotation of the handle on the opposite side of the door is not prevented but is ineffective to release the latch.

Preferably the shaft is permanently coupled in the rotational sense to an internal release element or elements which it controls, displacement of the shaft serving to uncouple it from the opposite side door handle. The shaft may have a portion of square section normally engaging a corresponding aperture in the opposite side door handle for rotation therewith, and a circular or otherwise reduced section which engages and can turn freely within said aperture when the shaft is in the locking position. The shaft conveniently remains permanently coupled to the other or locking side door handle.

The shaft may project through and from that handle to form, in effect, a pushbutton which is depressed to lock the latch. Alternatively the shaft may have a lateral projection of trigger-like form which can be pulled to the locking position by the index finger of a hand by which the associated door handle is grasped.

A return spring preferably urges the shaft to the normal position and against which it is displaced to the locking position, and detent or index means may be provided which automatically come into operation when the shaft is displaced to the locking position and act to retain it in that position. The arrangement may be such that release of the latch by means of the locking side handle automatically frees the detent and allows the shaft to return to its normal position under the influence of the return spring.

A self-cancelling arrangement may be provided which acts to release the shaft and allows it to return to the normal position if the door is closed when the shaft is in the locking position. To this end the latch member, which is conveniently a slam bolt, may be arranged to engage the detent means during door closure to free the detent if the latter is operative at the commencement of door closure.

The invention will now be further described with reference to the accompanying drawings which illustrate, by way of example, two forms of mortice door latch

2

of the slam-bolt type in accordance with the invention, and in which:

FIGURE 1 is a view of a portion of the corresponding edge of a door with one of the mortice latches in position therein,

FIGURE 2 is a sectional view on the line II—II in FIGURE 1 showing the associated door handles and the adjacent frame structure,

FIGURE 3 is a sectional view on the line III—III in FIGURE 2,

FIGURE 4 is a sectional view on the line IV—IV in FIGURE 3,

FIGURE 5 is a sectional view on the line V—V in FIGURE 3, and

FIGURE 6 is a view corresponding to that of FIGURE 2 but of the other mortice latch.

In each case the latch has a generally tubular housing 1 morticed into the door 2, the housing 1 having the usual end fixing flange 3. A sliding bolt 4 is mounted in the housing 1 and urged by a latch return spring 5 to a position in which it projects from the housing 1 for latching engagement in the normal manner with a keeper plate 6 which is mounted on the associated door frame 7. In the drawings the bolt 5 is shown in the latched position relatively to the keeper 6.

An internal release element 8 of generally tubular form is mounted in bearings in the housing 1 for rotation about an axis perpendicular to the plane of the door 2. The bolt 4 has an elongated cut-out aperture 9 through which the element 8 passes, and the latter has two relatively divergent projecting ears 10 which respectively engage the inner edges of upper and lower apertures 12 in the bolt 4 when the element 8 is turned. The apertures 12 are formed in upper and lower limbs 13 of a stem portion of the bolt 4 above and below the cut-out aperture 9. Engagement of one of the ears 10 by its outer surface 10a with the inner end of the corresponding aperture 12, on rotation of the element 8, acts to displace the bolt 4 and release the latch.

The element 8 has a central through aperture 14 of square cross-section, and rotation of the element 8 is mainly limited by engagement of the rear end of the bolt 4 with a stop face 11 in the housing 1. At the same time the inner surface 10b of the other ear 10 engages either the upper or lower surface of the cut-out aperture 9. An operating shaft 15 which passes through the releasing element 8 has a mid portion 16 of square cross-section which engages both the aperture 14 and a similarly shaped aperture 17 in a drive plate 18 of an inner door handle 19.

In each case the shaft 15 is axially displaceable from a normal or unlocked position (as shown in FIGURE 6), in which both door handles are operative to release the latch, to a locking position (as shown in FIGURES 2 and 3) in which the outer door handle 20 is inoperative to release the latch and turns freely on the shaft 15. Movement of the shaft 15 to the locking position takes place against the action of a return spring 22 which constantly urges the shaft 15 back to the normal or unlocked position.

In the latch of FIGURES 1 to 5 the shaft 15 is moved inwardly to the locking position (shown in full lines in FIGURE 2) by means of a lateral projection 23 of trigger-like form which is pulled to the locking position by the index finger of the hand by which the door handle 19 is grasped; in this case the return spring 22 is housed in the handle 19, and the projection 23 projects from the boss of the housing 19 through an axially directed slot 24. The shaft 15 has an outer end portion 25 of circular cross-section equivalent to the square portion 16 with the corners thereof rounded off.

The shaft 15 also passes through an aperture 26 in a drive plate 27 of the outer handle 20 which is of similar shape to the aperture 14, and as shown in FIGURE 2 in the locking position the shaft portion 25 is engaged within the aperture 26. Thus the drive plate 27 and hence the handle 20 can turn freely without turning the shaft 15. In the unlocked position of the shaft 15, as shown in broken lines in FIGURE 2, the square portion 16 of the shaft 15 engages all three apertures 14, 17 and 26 so that both handles 19 and 20 are operative to turn the shaft 15 and hence to release the latch.

Referring now to the latch of FIGURE 6, at the inner end the shaft 15 thereof is of plain cylindrical form and projects at 28 through and from the inner door handle 19 in the manner of a pushbutton. The inner end 28 can be depressed manually to move the shaft from the normal position shown in FIGURE 6 to the locking position against the spring 22. Again the length of the mid portion 16 of the shaft 15 is such that in both positions of the latter it permanently couples the inner door handle 19 to the internal releasing element 8 in the rotational sense.

At the outer end the shaft 15 of FIGURE 6 has a square end portion 29 which in the normal position engages the squared aperture 26 in the drive plate 27 of the outer door handle 29, so that as shown the handle 20 is again normally operative to release the latch. In this case the return spring 22 is housed in the handle 20 so that the shaft 15 is urged inwardly to the normal position, and when the shaft 15 is moved to the locked position a rounded portion 30 of the shaft intermediate the square portions 16 and 29 engages the aperture 26 in the outer drive plate 27 and is freely rotatable therein in the same manner as the shaft portion 25 of the arrangement of FIGURES 1 to 5. Thus, on any attempt to open the door from outside the door handle 20 in both cases turns freely without releasing the latch and can be said to "freewheel."

A detent bolt 32 aligned with the latch bolt 4 is mounted in the housing 1 on the side of the shaft 15 remote from the edge of the door 2, and the bolt 32 is urged by a detent spring 33 into engagement with the shaft 15. When the shaft 15 is moved to the locking position (as shown in FIGURE 2) the detent bolt 32 is aligned with a lateral notch 34 in the mid portion 16 of the shaft and engages the notch 34 to retain the shaft 15 in the locking position when the latter is moved thereto, either by pulling on the projection 23 of FIGURE 2 or depressing the end 28 of FIGURE 6.

The notch 34 has an arcuate base which terminates at each end at the normal periphery of the shaft 15. Thus release of the latch by the inner door handle 19, when the door is locked and the bolt 32 engaged in the notch 34, has an initial smooth camming action on the bolt 32 which is displaced inwardly by the base of the notch 34 towards a position in which the shaft 15 is free to return to the normal position under the action of the return spring 22. Final displacement of the detent bolt 32 to this position results from engagement of a shoulder 35 on the plunger 34 by the rear face 36 of the bolt 4 as the latter is moved inwardly to the unlatched position. At the inner end the bolt 4 has an aperture 37 from the face 36 into the cut-out aperture 9 and through which the bolt 32 projects.

A self-cancelling arrangement is provided which prevents the door from being closed and latched with the shaft 15 retained in the locking position. To this end the latch bolt 4, during latching, engages and displaces the detent bolt 34 in the manner just described if the bolt 32 is in the shaft retaining position when the door is closed. As described, such displacement of the detent bolt 32 is sufficient to free the detent and allow the shaft 15 to return to the normal position.

In addition to the normal leading edge bevel 38 which is of curved form and engages the keeper plate 6 during door closure to move the bolt 4 inwardly in the usual manner, the outer end of the bolt 4 has a trailing bevel

39 which normally engages the keeper 6 to hold the door closed. The bevel 39 is, as shown in FIGURES 2 and 6, relatively steep and acts so that for all normal purposes the door is firmly latched but can, in the event of an emergency, be opened from outside by the application of a sufficient door opening force.

The necessary door opening force depends upon the frictional characteristics of the material from which the bolt 4 and the keeper 6 are manufactured and the angle of the bevel 39, and these are normally so related that an opening force of the order of 100 lbs. is necessary to force the door; this is chosen as a force which would not normally be applied accidentally but which can easily be applied by a single person if necessary. Latches of the type described are commonly used with bathrooms and the like so that they can be locked from inside, and it is with such rooms that it is at times necessary to gain access in an emergency when the door is locked. The illustrated bolt formation provides a novel arrangement in which entrance can be gained in an emergency without damaging the door or latch structure and without the use of tools. With previous forms of latches a locked door can only be opened in an emergency either by applying a damaging and excessive opening force and/or by the use of tools.

I claim:

1. A door latch comprising a housing, a latch bolt slidably mounted in said housing, a latch spring urging the bolt to the latching position in which it projects from the outer end of said housing, an operating shaft adapted to be rotationally coupled to door handles respectively mounted on opposite sides of the door, said bolt being apertured to allow passage of said shaft laterally therethrough and the shaft being axially displaceable from one side of the door from a position in which rotation of the handles withdraws the bolt from the latching position to release the latch to a locking position in which the shaft is inoperative on turning the handle on the other side of the door to release the latch, and detent means which are mounted in the bolt on the inner side of the shaft and automatically come into operation when the shaft is displaced to the locking position and act to retain the shaft in that position, the detent means being automatically disengaged from the shaft on inward movement with the latch bolt from the latching position.

2. A door latch according to claim 1, wherein the shaft is permanently coupled in the rotational sense to an internal release element or elements which it controls, displacement of the shaft to the locking position serving to uncouple the shaft from the opposite side door handle.

3. A door latch according to claim 2, wherein the shaft has a portion of square cross-section normally engaging a corresponding aperture in the opposite side door handle for rotation therewith and a reduced section which engages and can turn freely within said aperture when the shaft is in the locking position.

4. A door latch according to claim 3, wherein the shaft remains permanently coupled to the locking side door handle.

5. A door latch according to claim 4, wherein the shaft has a lateral projection by which it can be moved to the locking position.

6. A door latch according to claim 5, wherein the lateral projection is of trigger-like form and when fitted projects between the locking side door handle and the door.

7. A door latch assembly comprising a housing, a latch bolt slidably mounted in said housing, a latch spring urging the bolt to the latching position in which it projects from the outer end of said housing, an operating shaft, first and second door handles respectively mounted on opposite sides of the door and from and through the first of which said shaft projects in the manner of a pushbutton, a return spring urging said shaft to the projecting position, and a release element mounted on the shaft and

rotatable therewith to engage and displace said bolt from the latching position, said bolt being apertured to allow passage of said shaft laterally therethrough and the shaft being axially displaceable against said return spring from a position in which the shaft is rotationally coupled to both handles to a locking position in which the shaft is not rotationally coupled to the second handle and hence is inoperative to release the latch on turning of said second handle, and detent means which are mounted in the bolt on the inner side of the shaft and automatically come into operation when the shaft is displaced to the locking position and act to retain the shaft in that position, and are automatically released on inward movement of the bolt from said latching position.

8. A door latch according to claim 7, wherein the detent means comprise a detent bolt which is aligned with and engages a notch in the shaft when the latter is in the locking position.

9. A door latch according to claim 7, wherein the latch member is a slam bolt which is formed on the trailing side with a steep bevel which, when latched, enables a door with which the latch is used to be opened in an emergency by the application of a non-damaging opening force to the door.

10. A door latch comprising a housing, a latch bolt slidably mounted in said housing, a latch spring urging the bolt to the latching position in which it projects from said housing, an operating shaft rotationally coupled to door handles respectively mounted on the inner and outer sides of the door, said bolt being cut away to allow passage of said shaft laterally therethrough and the shaft being accessible from said inner side of the door, and being axially displaceable from a normal position in which rotation of either handle withdraws the bolt from the latching position to release the latch to a locking position in which the shaft is inoperative to release the latch from

said outer side of the door, a return spring urging the shaft to said normal position, a release element mounted on said shaft within the cut-away section of said bolt and adapted to engage the bolt on rotation of said shaft to withdraw the bolt against said latch spring, and a detent bolt mounted in the latch bolt on the inner side of the shaft and which on displacement of the shaft to the locking position is aligned with and engages a notch in the shaft and acts to retain the shaft in that position, whereby withdrawal of the bolt, either by rotation of said inner side handle or on door closure, should the latter be open, will cause movement of the detent bolt with the latch bolt to free the shaft which then returns to the normal position under the return spring force.

15 11. A door latch according to claim 10, wherein said shaft has a multi-sided cross-section for engagement with said door handles and said release element and a reduced cross-section which engages and allows the outer side door handle to turn freely when the shaft is in the locking position; the housing latch bolt, latch spring, release element and detent bolt forming a single assembly which can be fitted complete as such from the adjacent edge of the door.
